UNITED STATES PATENT OFFICE.

JOHN W. JACKSON, OF DETROIT, MICHIGAN, ASSIGNOR OF ONE-HALF TO ADA ALBERTA JACKSON, OF BRIGHTON, MICHIGAN.

RAILROAD-CROSSING SIGNAL.

Application filed April 9, 1923. Serial No. 630,782.

To all whom it may concern:

Be it known that I, JOHN W. JACKSON, a citizen of the United States, residing at Detroit, in the county of Wayne and State 5 of Michigan, have invented certain new and useful Improvements in Railroad-Crossing Signals, of which the following is a specification.

This invention relates to improvements 10 in railroad crossing signals and has for its prime object to provide a signal that will indicate to automobilists and others from either side of the railroad track the approach of a railroad train.

15 A further object of the invention is to provide a railroad crossing signal that will indicate the direction from which the train is approaching the crossing.

A still further object of the invention 20 is to provide a crossing signal, wherein a circuit will be automatically closed upon the approach of a train and the word "Stop" or "Caution" will be illuminated on both sides of a casing mounted on a post 25 in the roadway.

And a still further object of my invention 30 is to provide an audible signal in connection with a visible signal, which will give a double warning of the approach of a railroad train.

Another object of the invention is to provide a railroad crossing signal of the above indicated character, which is simple in construction, durable, efficient for the purpose 35 intended, and one that can be constructed and installed at all railroad crossings at a relatively low cost.

These and like objects of the invention 40 will be better understood as the description follows and as is specifically pointed out in the appended claims.

Referring to the accompanying drawings 45 which form a part of this specification and which clearly illustrate the construction and operation of my invention,

Figure 1 is a perspective view of a traffic signal constructed in accordance with my invention.

Figure 2 is an enlarged front elevation, 50 partly in section.

Figure 3 is a vertical section through my traffic signal, and

Figure 4 is a plan view of the wiring system.

55 Referring to the accompanying drawings

in detail, like characters will be used to designate like parts in the different views.

In the drawings, the numeral 1 indicates a post which is adapted to be mounted in any suitable position in the roadway at one 60 side of a railroad track. Adjacent the upper end of the post, same is provided with a pair of outwardly extending arms 2, on which any suitable indicia such as "Railroad crossing" is painted thereon.

A casing 3 having a glass front and back 65 is mounted on the post 1 and the outwardly extending arms 2. The glass cover on both the front and rear is divided by means of a partition 4, and the upper glass 5 is preferably formed of red, while the lower glass 6 is constructed of white or green. Such indicia as "Traffic stop" is painted or perforated in the glass 5, while such wording as "Traffic go" is painted or perforated in 70 the glass 6. An electric bulb is mounted in the upper compartment formed by the top of the casing and the partition 4, for illuminating the indicia on the glass 5, while an electric bulb is positioned in the lower 75 compartment, formed by the partition 4 and a false bottom 7, the bulb in the lower compartment acting to illuminate indicia on the glass 6.

The casing 3 is provided with end walls 85 8 that are connected with the partition 4, bottom wall 7, and upper false wall 9, the end walls 8 terminating a sufficient distance from the edge of the casing to provide pockets 10 to provide means for receiving 90 therein a pivotally indicating hand or finger 11, each of said fingers being pivotally mounted as at 12, and one of the fingers being provided with the word "North", while the finger in the opposite end of the 95 casing has the word "South" thereon.

A pair of solenoids, designated by the numerals 13 and 14 respectively are mounted in the casing between the upper false top 9 and the top of the casing, which is indicated by the numeral 15. A core 16 is slidably mounted in each of the solenoids 13 and 14, and one end of each of the cores 16 has a cord 17 attached thereto as at 18. The said cords are adapted to pass over a pulley 19 105 and be connected to the hand or finger 11 as at 20.

The solenoids 13 and 14 are connected to wires 21 carried by telegraph poles alongside the railroad track, said wires being attached 110

to suitable circuit switches 21' positioned alongside the railroad tracks which are arranged to be engaged by the wheels of a train for closing a circuit to the signal while 5 the train is passing thereover. The switches 21' are placed sufficient distances from the signal on both sides thereof, so that by the time the last wheels of a train of ordinary length have disengaged the same, the motive 10 of the train will be clearly visible at the crossing. One of the switches is located on the south bound track and the other on the north bound track, so that the signal will operate when trains approach 15 from either direction, for example when a train is approaching from the south, the switch 21' leading to the solenoid 13 will be closed, thus energizing the same and causing the core 16 to slide therein, thus 20 bringing the arm 11 on its pivot to display the word "South", thus indicating that the train is approaching from the south. At the same time, the electric bulb in the upper compartment is ignited, which illuminates 25 the words "Traffic stop", which will give sufficient warning to automobilists at a considerable distance in order to enable them to bring the automobile to a stop before reaching the crossing. When a train is ap- 30 proaching from the north, the operation described above is reversed, the solenoid 14 being energized in this case, causing the arm 11 carrying the word "North" to swing outwardly. 35 As soon as the last car of the train has passed the switch 21' located on the track on which the train is traveling, the circuit is broken, thus deenergizing either the solenoid 13 or 14, allowing the arm or finger 11 to 40 move downwardly to an inoperative position, and at the same time, a solenoid 22 suitably connected through wires 22' to the wires 21, and positioned between the false bottom 7 and the bottom 23 of the casing 45 is deenergized, allowing the switch arm 24 to be closed under the influence of a spring arm 25, which will ignite the electric bulb in the lower compartment, thus displaying the words "Traffic go".

A bell 26 is mounted on the post 1 and 50 can be caused to sound an alarm by any suitable electric circuit leading thereto.

While I have shown and described the preferred form of my invention, I realize that various minor changes may be resorted 55 to, without departing from the spirit and scope of the invention as claimed, and therefore, I do not wish to limit myself to the exact details of construction shown, nor to the combination and arrangement of parts. 60

What I claim as new and desire to secure by Letters Patent is:

1. A railroad crossing signal comprising a post mounted at one side of a railroad crossing, a casing supported on said post, 65 an upper and lower compartment formed in said casing, said compartments having glass covers on the front and rear thereof and having indicia thereon, electric bulbs positioned in said compartments for illuminating the indicia, a pocket formed on each end of said casing, a movable hand normally received in each of said pockets, and means for illuminating the indicia in one compartment and moving one of said hands so as 70 to be visible upon the approach of a train, and illuminating the other compartment and returning the hand so as to not be visible after the train has passed.

2. In a railroad crossing signal, comprising a post mounted at one side of a railroad crossing and having a casing supported thereon, an upper and lower compartment formed in said casing, said compartments having glass covers on the front and rear 85 thereof and having indicia thereon, electric bulbs positioned in said compartments for illuminating the indicia, a movable hand in each side of said casing, and means for illuminating the indicia in one compartment 90 and moving one of said hands upon the approach of a train, and illuminating the other compartment and returning the hand after the train has passed.

In testimony whereof, I have affixed my 95 signature.

JOHN W. JACKSON.
